UNITED STATES PATENT OFFICE.

HARRY E. RUCKERT, OF PHILADELPHIA, PENNSYLVANIA, ASSIGNOR, BY MESNE ASSIGNMENTS, TO SANITARY PRODUCTS CORPORATION OF AMERICA, OF PHILADELPHIA, PENNSYLVANIA, A CORPORATION OF VIRGINIA.

METHOD OF MAKING SPOONS.

Application filed January 12, 1925. Serial No. 1,779.

This invention relates to the manufacture of spoons and similar table utensils from tin plate or other sheet metal stock, and has for its object the production of an inexpensive 5 article of the character referred to, solely by the blanking out and die forming process, and without subsequent finishing, which article will nevertheless have sufficient strength and rigidity to perform its intended function 10 in a satisfactory manner, and which will have no sharp edges to cause injury to the mouth or hands of the user.

The foregoing and other objects of the invention will best be understood from the following description of one embodiment thereof and the method of producing the same, as illustrated in the accompanying drawings. It will be understood, however, that the particular construction, operations, appliances, 20 and material described and shown have been chosen for illustrative purposes merely, and that the invention, as defined by the claims hereunto appended, may be otherwise embodied and practised without departure from 25 the spirit and scope thereof.

In said drawings:

Fig. 1 is a simplified sectional view of the punch elements for blanking out the articles from the sheet metal stock.

30 Fig. 2 is a plan view of one of the blanks produced by the punch elements shown in Fig. 1.

Fig. 3 is an enlarged section on the line 3—3, Fig. 2.

35 Fig. 4 is a simplified sectional view of a set of dies for shaping a blank such as that shown in Fig. 2 into the form of a spoon.

Fig. 5 is a plan view of a spoon formed by the dies shown in Fig. 4.

40 Fig. 6 is an enlarged section taken substantially on the line 6—6, Fig. 5.

Fig. 7 is a view similar to Fig. 4 of dies arranged in accordance with one feature of the present invention.

45 Fig. 8 is an enlarged and inverted transverse section, taken substantially on the line 8—8, Fig. 7, of the spoon formed by the dies shown in the latter figure.

Fig. 9 is a similar view on the line 9—9, 50 Fig. 7, illustrating a hypothetical construction.

Fig. 10 is a transverse section, taken substantially on the line 10—10, Fig. 7, of the dies shown in the latter figure.

Fig. 11 is a plan view of a spoon produced 55 by the dies shown in Figs. 7 and 10.

Fig. 12 is a section on the line 12—12, Fig. 11.

In the manufacture of sheet metal tableware, the tin plate or other sheet metal stock 60 15 (Fig. 1) is passed between blanking-out dies comprising a reciprocating punch 16 and a cooperating hollow punch die 17 which operate to punch from said stock blanks 18 of the proper configuration, as shown, for 65 example, in Fig. 2. In the operation of punching out blanks by means of instrumentalities of the character referred to, the edges of the blank, where they are sheared from the stock, are turned slightly in the direction of that face of the blank which is engaged by the punch 16, as shown at 19 in Fig. 3, so that said edges present, at that face of the blank, sharp, projecting burrs or ridges 20, said edges being correspondingly 70 75 rounded at the opposite face of the blank, as shown at 21.

In the manufacture of spoons of the type to which the present invention relates, the blanks 18 are shaped into the desired form 80 by and between complementary forming dies of the general type shown at 22 and 23 in Fig. 4, the shape of said dies, as shown, being such as to produce a spoon or similar utensil 24 (Fig. 5) by bending the blank in 85 one direction to form a concavo-convex bowl 25 and in the opposite direction to form a handle 26 substantially U-shaped in cross section with its convexity opposite that of the bowl, said handle being substantially 90 straight from its outer end to the point where it merges with the bowl. As shown in Fig. 4 the dies 22 and 23 are so shaped that the bowl 25 is formed with its concave side at that face of the blank which was engaged by 95 the punch 16 and toward which the edges 19 have been turned. When so formed, the sharp burrs or ridges 20 are brought to the upper side of the bowl, as shown in Fig. 6, thereby resulting in the presence, along the 100 upper rim of the bowl, of sharp edges which tend to cut the upper lip of the user, unless removed by a buffing or other finishing operation which adds materially to the cost of the spoon. Utensils of this type are designed 105 for only temporary use and are sold at a very low price, so that the element of production cost is important.

To overcome the above difficulty, dies 27 and 28 arranged as shown in Fig. 7 may be employed. The configuration of the dies 27 and 28 is such that the blank is shaped 5 to form a spoon 29 whose bowl 30 is disposed with its convex side at that face of the blank which was engaged by the punch 16 and toward which the edges 19 have been turned. As a result, the rounded edges 21 10 of the blank are brought uppermost, as shown in Fig. 8, so as to provide a smooth rim to the bowl without any special subsequent finishing operation, the sharp edges being turned downwardly where they cannot 15 engage the upper lip of the user nor his lower lip which is held away from said edges by the convexity of the bowl.

As in the case of the spoon 24, the handle 31 of the spoon 29 is substantially 20 straight and U-shaped in cross-section with its convexity opposite that of the bowl, so that when formed as last described the sharp edges 20 of the blank are brought to the bottom of the handle, as shown in Fig. 9. 25 In this position said edges tend to cut the thumb and fingers of the user, and in order to prevent such injury the dies 27 and 28 are, in accordance with the present invention, so formed as to flatten the turned edges 30 19 of the blank at the sides of the handle. This is preferably accomplished by so forming the dies 27 and 28 as to turn said edges outwardly, as shown in Fig. 10, to form longitudinally extending, substantially coplanar lands or stiffening flanges 32 (see 35 also Figs. 11 and 12) at the sides of the handle 31 and connecting with the bowl 30. By the formation of these lands on the handle of the spoon, the burrs on the said handle are, during the forming operation, disposed in and under the corresponding flat opposed faces of the forming dies, and are therefore crushed or dulled by the final action of the dies.

40 The resulting spoon may therefore be produced by a simple process from inexpensive material but is nevertheless entirely free from sharp edges which might tend to injure either the mouth or the hands of the user, the design being such that the sharp burrs along the edges of the handle, which result from the manipulation of the blank necessary to avoid such burrs at the upper edges of the bowl, are effectively eliminated 45 by the forming dies during the forming operation by their conversion into the flat lands

or flanges 32. These lands or flanges not only provide smooth lower edges on the handle, but serve to stiffen in the lateral direction the entire structure, particularly the 60 handle 31, which is adequately stiffened in the vertical direction by its U-shaped cross-section, thereby providing a straight handle of simple design and graceful form but of fully adequate strength and rigidity. 65

What I claim is:

1. The herein described method of making a spoon or the like which consists in punching a blank from sheet metal stock and simultaneously turning the edges of said blank in the direction of one of the faces thereof, shaping said blank to form a bowl with its convex side at the face of the blank toward which said edges are turned and a handle substantially U-shaped in cross section with its convexity opposite that of the bowl, and flattening the portions of the turned edges of the blank along the sides of said handle. 75

2. The herein described method of making a spoon or the like which consists in punching a blank from sheet metal stock and simultaneously turning the edges of said blank in the direction of one of the faces thereof, bending said blank in one direction to form a concavo-convex bowl with its convex side at the face of the blank toward which said edges are turned, and simultaneously bending said blank in the opposite direction to form a handle substantially U-shaped in cross-section with its convexity opposite that of the bowl, and flattening the edges of the blank along the sides of said handle. 80

3. The herein described method of making a spoon or the like which consists in punching a blank from sheet metal stock and simultaneously turning the edges of said blank in the direction of one of the faces thereof, shaping said blank to form a bowl with its convex side at the face of the blank toward which said edges are turned and a handle substantially U-shaped in cross-section with its convexity opposite that of the bowl, and turning outward the edges of said handle to form longitudinally extending, substantially coplanar lands or flanges at the sides thereof. 95

In testimony whereof I affix my signature.

HARRY E. RUCKERT.
